Variety denomination: 'KLEDP16186'.

**CROSS-REFERENCE TO RELATED
APPLICATIONS**

A Community Plant Variety Rights application for the instant variety was filed on May 6, 2016, File No. 2016/1116. 'KLEDP16186' has not been sold or made publicly available more than one year prior to the filing of the instant application.

BACKGROUND OF THE NEW PLANT

The present invention comprises a new and distinct variety of *Dianthus*, botanically known as *Dianthus caryophyllus*, and hereinafter referred to by the variety name 'KLEDP16186'. 'KLEDP16186' originated from a branch mutation of the proprietary mutation parent 'KLEDP07088' (unpatented) in March 2010 in Stuttgart, Germany.

In August 2012, 'KLEDP16186' was first vegetatively propagated by vegetative cuttings. 'KLEDP16186' was found to reproduce true to type in successive generations of asexual propagation in Stuttgart, Germany via vegetative cuttings.

SUMMARY

The following are the most outstanding and distinguishing characteristics of this new variety when grown under normal horticultural practices in Stuttgart, Germany.

1. Dark-purple flowers with white margins;
2. A strong fragrance; and
3. An upright habit.

DESCRIPTION OF THE PHOTOGRAPH

This new *Dianthus* plant is illustrated by the accompanying photograph of a plant approximately 2 to 3-months

old and grown in a greenhouse in Stuttgart, Germany. The photograph shows the whole plant, including the flowers and foliage and buds and was taken in April 2016 in Stuttgart, Germany.

5 The colors shown are as true as can be reasonably obtained by conventional photographic procedures.

DESCRIPTION OF THE NEW VARIETY

10 The following detailed descriptions set forth the distinctive characteristics of 'KLEDP16186'. The data which define these characteristics were collected from asexual reproductions carried out in Stuttgart, Germany. Data was collected in April 2017 on 7-month old plants grown in a plastic greenhouse. Color references are to The R.H.S. Colour Chart of The Royal Horticultural Society of London (R.H.S.), 5th edition (2007).
